UNITED STATES PATENT OFFICE.

ROBERT L. HOOVEN, OF WASHINGTON, DISTRICT OF COLUMBIA.

ENGINE-HOOD COVER.

1,285,185.

Specification of Letters Patent. Patented Nov. 19, 1918.

Application filed April 19, 1913, Serial No. 762,394. Renewed December 1, 1917. Serial No. 205,001.

To all whom it may concern:

Be it known that I, ROBERT L. HOOVEN, a citizen of the United States, residing at 1421 Irving street, N. W., Washington, D. C., have invented new and useful Improvements in Engine-Hood Covers, of which the following is a specification.

The object of the present invention is to provide for regulating the exposure to the atmosphere of the radiating surface of a radiator for the internal combustion engines of automobiles.

The present embodiment of the invention is that of a cover capable of being conveniently fitted to and retained in place upon a radiator, provision being made for entirely cutting off the radiating surface from the atmosphere, for exposing a portion only of the radiating surface and also for exposing the entire radiating surface, whereby, an effective regulation may be obtained in a convenient and satisfactory manner.

The present radiator cover has been shown in the accompanying drawings associated with an engine hood cover, but it will, of course, be understood that the present invention is not necessarily dependent upon the engine hood cover.

Figure 1 is a view in side elevation of this invention in position upon the engine hood of an automobile.

Fig. 2 is a view in front elevation of Fig. 1.

Fig. 3 is a view in longitudinal vertical section through the cover with the rear broken away.

Fig. 4 is an enlarged detail view in section illustrating the manner of attaching the front to the main body of the cover.

Corresponding and like parts are referred to in the following description and indicated in all the views of the accompanying drawings by the same reference characters.

The engine hood cover comprises a body portion 1. The radiator cover is designated by the numeral 2. These members are preferably composed of two thicknesses of material. The outer material 3 being oil-cloth or other suitable water-proof material and the inner material 4 being of felt, fabric, or any other suitable heat non-conducting material. A series of studs 5 is mounted at the forward edge of the engine hood cover 1 and are adapted to engage eyelets 6 provided at the edge of the radiator cover 2,

These studs and eyelets may be of any pattern or design as now generally employed. A circular aperture 7 is provided at the forward edge of the engine hood cover 1 and is adapted to receive the filler nipple 8 of the water radiator of the engine. The radiator cover 2 is provided with a recess 9 which also receives the said nipple. The edge of the radiator cover 2 is adapted to lie over the forward edge of the engine hood cover 1 and the said radiator cover 2 is provided with flap 10 which is adapted to lie under the forward edge of the engine hood cover 1. Straps 11 are secured to the intermediate part of the engine hood cover 1 in the vicinity of the lower edge thereof and are adapted to be passed through the usual hood handles and are secured at their ends by means of studs 12 fixed to the intermediate part of the engine hood cover 1.

The radiator cover 2 is provided with an opening 15 designed to expose a portion of the radiating surface of the radiator to the atmosphere. A flap 16 is secured along the upper edge of the opening 15 and is provided at its inner and outer sides with water-proof material. Between these layers of waterproof material the said flap 16 may be provided with a layer of heat non-conducting material. The flap 16 is provided at its free edge with an eye 17. A stud 18 is located upon the radiator cover 2 at the lower edge of the opening 15 and is adapted to be engaged by the eye 17 of the flap 16. A stud 19 is located upon the radiator cover 2 in the vicinity of the upper edge thereof and is adapted to be engaged by the eye 17 when the flap 16 is swung to an open position.

From the above description it will be seen that means is provided for leaving exposed a portion of the radiator or the said radiator may be completely covered as desired. Furthermore when the flap 16 is swung down and secured, the circulation of air through the opening 15 of the radiator cover is completely interrupted.

When it is desired that a regulated amount of air should circulate through the radiator, the flap 16 is raised and secured in its elevated position. When it is desired that a free circulation of air pass through the radiator, the radiator cover 2 is removed.

For these reasons it will be seen that a simple and effective means for regulating

the exposure of the radiator is provided which means may be regulated to meet any and all conditions that the engine may require. At the same time the parts of the cover may be adjusted in order to meet the conditions of temperature or weather.

What I claim is:

1. A cover for the hood and radiator of an internal combustion engine, comprising a body portion of a size and shape to fit over the sides and top of an engine hood, and a front portion secured to the body portion and of a shape and size to lie across and completely cover the front of the engine radiator, said front portion being provided with a ventilation opening located within the periphery of said front portion, said front portion having parts surrounding the opening and adapted to cover the front radiator surface at the top, bottom and upright sides of the ventilation opening, and a closing flap for said opening, said flap being secured at one of its edges to the front portion and adjacent one of the edges of the ventilation opening.
2. A cover for the hood and radiator of an internal combustion engine, comprising a body portion of a size and shape to fit over the sides and top of an engine hood, and a front portion secured to the body portion and of a shape and size to lie across and completely cover the front of the engine radiator, said front portion being provided with a ventilation opening located within the periphery of said front portion, said front portion having parts surrounding the opening and adapted to cover the front radiator surface at the top, bottom and upright sides of the ventilation opening, a closure flap for said opening, said flap being secured at one of its edges to the front portion

and adjacent one of the edges of the ventilation opening, and means for holding the closure flap closed and also open.

3. The combination with the radiator of an internal combustion engine, of a removable cover covering the front, top side and upright sides of the radiator and provided with an opening lying entirely within the periphery of the cover to expose a portion of the radiator, and a displaceable closure for said opening.

4. A cover for the radiator of an internal combustion engine, comprising a front provided with a ventilating opening lying entirely within the periphery of the front, a displaceable closure for said opening, and top and upright side flanges extending from the corresponding edges of the front at substantially right angles thereto for embracing and covering the top and upright sides of the radiator, and means on said flanges for detachably maintaining the cover in place upon a radiator.

5. A cover for the radiator of an internal combustion engine, comprising a front of substantially the size and shape of the front of a radiator, flanges at the top and upright sides of the front for embracing and covering the top and upright sides of the radiator, said front having a ventilating opening therein lying entirely within the periphery of the front, and a displaceable closure for the opening and carried by the front, said front, flanges, and closure being of flexible, waterproof and heat nonconducting material.
